United States Patent

Des. 242,089

Patented Nov. 2, 1976

242,089

SHOE

Daniel Raufast, Savigny-sur-Orge, France, assignor to Raufast & Fils, Savigny-sur-Orge, Essonne, France

Filed May 12, 1975, Ser. No. 576,267

Claims priority, application France Nov. 13, 1974

Term of patent 7 years

Int. Cl. D2—04

U.S. Cl. D2—272

FIG. 1

FIG. 3

FIG. 4

FIG. 1 is a top, left, perspective view of a shoe showing my new design;

FIG. 2 is a top, right, perspective view thereof;

FIG. 3 is a rear elevation view thereof; and

FIG. 4 is a front elevation view thereof.

The bottom of the shoe is plain and unornamented.

I claim:

The ornamental design for a shoe, substantially as shown and described.
